UNITED STATES PATENT OFFICE.

WILLIAM H. MINER, OF CHICAGO, ILLINOIS.

BRAKE-SHOE FOR RAILWAY-CARS.

No. 839,074.

Specification of Letters Patent.

Patented Dec. 18, 1906.

Application filed July 12, 1906. Serial No. 325,807.

To all whom it may concern:

Be it known that I, WILLIAM H. MINER, a citizen of the United States, residing in Chicago, in the county of Cook and State of Illinois, have invented a new and useful Improvement in Brake-Shoes for Railway-Cars, of which the following is a specification.

My invention relates to improvements in brake-shoes for railway-cars or other vehicles.

The object of my invention is to provide a brake-shoe of a simple, efficient, and durable construction capable of being cheaply and conveniently manufactured, which with a minimum weight of metal will afford a maximum amount of wear or effective braking or retarding action, in which all parts of the shoe will be securely locked together and the cast parts reinforced or strengthened, so that when the shoe becomes worn thin there will be little danger of breakage and no danger of parts of the shoe in case of breakage becoming entirely disconnected and dropping down upon the track, and thus derailing or endangering the train, and in which the connection between the shoe and its attaching-lug may be strong, safe, and secure.

My invention consists in the means I employ to practically accomplish this object or result—that is to say, it consists in a brake-shoe having a solid composite body comprising a cast-metal portion, preferably of cast-iron, and a tough, soft, or wrought-metal portion, preferably of steel plate, provided with a series of divergent lugs or prongs extending at angles from the back portion of the shoe-body through the same to the front or wearing-surface thereof, said tough or soft metal or steel plate member serving as a tough - metal back for the shoe and preferably having the attaching-lug formed integrally therewith and forged, clamped, or pressed up to the required shape and the lugs or prongs of said tough-metal or steel-plate member, which extend through the body of the shoe from back to front, forming in part the wearing-surface of the shoe and serving to increase the frictional or retarding action of the shoe and also to strengthen the cast portion and to lock and tie all parts thereof together, the divergent prongs of the tough-metal plate portion also serving to chill the adjoining surface of the cast-iron portion, and thus to increase the durability and wearing qualities of the shoe and the cast metal portion and the soft or tough metal plate por-

tion of the shoe being united into one solid composite mass. The tough-metal member is also preferably provided with integral reversely-turned flanges or lugs projecting in the opposite direction from the integral angle-prongs to reinforce the extreme ends of the cast-metal portion of the shoe, and I prefer also to provide the wearing-surface of the shoe with soft or tough metal inserts to increase the frictional action and wearing qualities of the shoe.

My invention also consists in the novel construction of parts and devices and in the novel combinations of parts and devices herein shown or described.

In the accompanying drawings, forming a part of this specification, Figure 1 is a back view of the brake-shoe embodying my invention. Fig. 2 is a front view. Fig. 3 is a side elevation. Fig. 4 is a central longitudinal section on line 4 4 of Fig. 1. Fig. 5 is a detail section on line 5 5 of Fig. 4.

In the drawings, A represents the cast-metal portion of the shoe, and B the tough, soft, or wrought-metal or steel-plate portion thereof, about which the cast-iron portion A is cast, so as to intimately and perfectly unite the two portions A and B into one solid composite mass. The tough-metal portion B is furnished with a series of divergent integral prongs b, stamped up from the steel plate and extending at different angles to each other through the body of the shoe from the front to the back, so that the front edges b' thereof will constitute a portion of the wearing-surface D of the shoe during the whole life of the shoe as it wears thinner and thinner in use. The angle-prongs b or some of them are also preferably furnished with holes or openings b² through the same, so that when the iron or cast metal is cast about the soft or steel plate portion B it may extend continuously from one end of the shoe to the other in one solid continuous mass through the prongs as well as on each side thereof or beyond the edges thereof. The prongs b are narrower than the tough-metal or plate portion B of the shoe, so that this plate B has a skeleton portion b³ to form a continuous tough-metal back for the shoe. The attaching-lug b⁴ is preferably an integral loop stamped, pressed, or forged up from the steel or tough-metal back plate B, and it is formed before the cast-iron or cast-metal portion A is cast through and upon the tough soft metal or plate-steel

portion B. The centering-lugs *a a* are preferably of cast-iron and project over the end portion *b⁵* of the soft-metal or plate-steel portion B. At each end the plate-steel portion B is furnished with integral reversely-turned flanges or anchoring-lips *b⁶*, which are preferably bent about as illustrated in the drawings and which serve to reinforce the extreme end of the cast portion of the shoe-body.

To form the integral angle-prongs *b*, the steel plate is cut along the lines *b' b⁸*, the cuts *b⁸ b⁸* for each prong being preferably divergent, so each prong acts as a dovetail, considered separately or individually, in uniting and locking together the iron and steel-plate portions of the shoe, while at the same time each pair of prongs *b b*, by reason of their extending at divergent or different angles from each other, also serve to further lock and tie together the cast-iron and steel-plate portions of the shoe.

F F are soft or tough metal inserts embraced by the cast portion A of the shoe and extending transversely across the wearing-face thereof and arranged, preferably, about as indicated in the drawings, between the outer ends or wearing-faces of the integral divergent prongs *b* of the tough-metal portion B of the shoe.

When the cast-iron or cast-metal portion A of the shoe is cast through and about the tough, soft, or steel plate portion B of the shoe, the divergent prongs *b* serve to chill the iron or cast metal adjacent thereto, and thus to harden and strengthen the same and increase its durability and wearing qualities. Both portions A and B of the shoe thus mutually coact and coöperate to produce a composite shoe-body in which the frictional, heat-conveying, wearing, and structural qualities of each depends upon and is modified by the other and together form a composite and solid or integral mass of great strength and durability and which is peculiarly adapted to serve as an efficient brake-shoe, while at the same time the construction is such as to be capable of cheap and economical manufacture.

The divergent transverse prongs *b* being each wide or blade-like and extending transversely across the longitudinally central cast-metal portion of the body of the shoe are each individually large enough to have a material chilling and hardening action upon the adjacent cast-metal portion of the shoe and serve in a measure like partitions to separate the cast-metal portion into a number of constituent segments, all of which, however, are intimately united together and also with the wide divergent prongs themselves into one composite and solid or integral mass and of great strength and durability and having peculiarly effective wearing qualities by reason of the efficient chilling action of the wide di-

vergent prongs upon the cast-metal portion of the body of the shoe.

I claim—

1. A brake-shoe having a solid composite body comprising a cast-metal portion and a tough-metal portion, said tough-metal portion having integral divergent wide transverse prongs extending through the body of the shoe from the back to the front and said prongs constituting in part the wearing-surface of the shoe, and serving to transversely separate and chill the longitudinally central cast portion of the body of the shoe, substantially as specified. 75

2. A brake-shoe having a solid composite body comprising a cast-metal portion and a steel-plate portion provided with divergent wide transverse prongs extending through the body of the shoe from the back to the front and constituting part of the wearing-surface of the shoe, and serving to transversely separate and chill the longitudinally central cast portion of the body of the shoe, substantially as specified. 80 85

3. A brake-shoe having a solid composite body comprising a cast-metal portion and a tough-metal plate portion provided with divergent wide transverse prongs extending through the body of the shoe from the back to the front and constituting part of the wearing-surface of the shoe, and serving to transversely separate and chill the longitudinally central cast portion of the body of the shoe, said integral prongs having each divergent or dovetail acting side cut edges, substantially as specified. 90 95 100

4. A brake-shoe having a solid composite body comprising a cast-metal portion and a tough-metal plate portion provided with divergent wide transverse prongs extending through the body of the shoe from the back to the front and constituting part of the wearing-surface of the shoe, and serving to transversely separate and chill the longitudinally central cast portion of the body of the shoe, said tough-metal plate portion having a skeleton back part, substantially as specified. 105 110

5. A brake-shoe having a solid composite body comprising a cast-metal portion and a steel-plate portion provided with divergent wide transverse prongs extending through the body of the shoe from the back to the front and constituting part of the wearing-surface of the shoe, and serving to transversely separate and chill the longitudinally central cast portion of the body of the shoe, said divergent prongs having openings through the same, substantially as specified. 115 120

6. A brake-shoe having a solid composite body comprising a cast-metal portion and a steel-plate portion provided with divergent wide transverse prongs extending through the body of the shoe from the back to the front and constituting part of the wearing-surface of the shoe, and serving to trans- 125 130

versely separate and chill the longitudinally central cast portion of the body of the shoe, said steel-plate portion having an integral stamped-up attaching-loop, substantially as specified.

7. A brake-shoe having a solid composite body comprising a cast-metal portion and a tough-metal plate portion provided with divergent prongs extending through the body of the shoe from the back to the front and constituting part of the wearing-surface of the shoe, said tough-metal plate portion having an integral stamped-up attaching-loop and said cast portion having centering-lugs at each end of the shoe, substantially as specified.

8. A brake-shoe having a solid composite body comprising a cast-metal portion and a steel-plate portion provided with divergent wide transverse prongs extending through the body of the shoe from the back to the front and constituting part of the wearing-surface of the shoe and serving to transversely separate and chill the longitudinally central cast portion of the body of the shoe, and said plate portion having anchoring lips or flanges at its ends, substantially as specified.

9. A brake-shoe having a solid composite body comprising a cast-iron portion A and a tough-metal plate portion B, the latter forming a skeleton tough-metal back and being provided with integral wide transverse prongs extending through the cast-iron portion from the back to the front and constituting part of the wearing-surface of the shoe, and serving to transversely separate and chill the longitudinally central cast portion of the body of the shoe, substantially as specified.

10. A brake-shoe having a solid composite body comprising a cast-iron portion A and a plate-steel portion B, the latter forming a skeleton plate-steel back and being provided with integral prongs extending through the cast-iron portion from the back to the front and constituting part of the wearing-surface of the shoe, said prongs having openings through the same, substantially as specified.

11. A brake-shoe having a solid composite body comprising a cast-iron portion A and a plate-steel portion B, the latter forming a skeleton plate-steel back and being provided with integral wide transverse prongs extending through the cast-iron portion from the back to the front and constituting part of the wearing-surface of the shoe, and serving to transversely separate and chill the longitudinally central cast portion of the body of the shoe, said prongs having divergent or dovetail acting side edges, substantially as specified.

12. A brake-shoe having a solid composite body comprising a cast-iron portion A and a

plate-steel portion B, the latter forming a skeleton plate-steel back and being provided with integral wide transverse prongs extending through the cast-iron portion from the back to the front and constituting part of the wearing-surface of the shoe, and serving to transversely separate and chill the longitudinally central cast portion of the body of the shoe, said prongs extending at different angles to each other, substantially as specified.

13. A brake-shoe having a solid composite body comprising a cast-iron portion A and a plate-steel portion B, the latter forming a skeleton plate-steel back and being provided with integral wide transverse prongs extending through the cast-iron portion from the back to the front and constituting part of the wearing-surface of the shoe, and serving to transversely separate and chill the longitudinally central cast portion of the body of the shoe, said plate-steel portion B having bent anchoring lips or flanges at its ends, substantially as specified.

14. A brake-shoe having a solid composite body comprising a cast-iron portion A and a tough-metal plate portion P, the latter forming a skeleton tough-metal back and being provided with integral prongs extending through the cast-iron portion from the back to the front and constituting part of the wearing-surface of the shoe, said tough-metal portion B having an integral attaching-lug for the shoe, substantially as specified.

15. A brake-shoe having a solid composite body comprising a cast-metal portion and a tough-metal portion, said tough-metal portion having integral divergent prongs extending through the body of the shoe from the back to the front and said prongs constituting in part the wearing-surface of the shoe, and tough-metal inserts in the cast portion of the shoe between said integral divergent prongs of the tough-metal portion thereof, substantially as specified.

16. A brake-shoe having a solid composite body comprising a cast-metal portion and a tough-metal portion, said tough-metal portion having integral divergent prongs extending through the body of the shoe from the back to the front and said prongs constituting in part the wearing-surface of the shoe, and tough-metal inserts in the cast portion of the shoe between said integral divergent prongs of the tough-metal portion thereof, said tough-metal portion of the shoe having bent reinforcing-flanges at the ends thereof to strengthen the cast portion of the shoe-body at the ends, substantially as specified.
